METHOD OF AND DEVICE FOR PRODUCING
CIGARSErnst Ruben Dahlström, Alsten, Sweden, assignor
to Aktiebolaget Formator, Stockholm, Sweden,
a joint-stock company of SwedenApplication November 20, 1931, Serial No. 576,383
In Sweden November 26, 1930

11 Claims. (Cl. 131—5)

The present invention relates to a method and apparatus for producing cigars of a type in which bunches are provided with wrappers in a rolling device, the wrappers being transferred to said rolling device by mechanical means from a device for cutting wrappers out of tobacco leaves.

It is thereby of importance that the output of finished cigars is as great as possible. The output can be increased by increasing the velocity of the machine, but only to a certain extent, as the operator or operators must have sufficient time for serving the machine in a satisfactory manner.

According to this invention the output is increased in a very simple way, so that the machine is able to produce the double number of cigars in a certain time or still more without requiring more service and without increasing the velocity of the machine working according to hitherto known methods. Even if the machine according to the invention works with a less velocity than hitherto known machines, it is possible to obtain a greater output, and in such case the advantage is attained that the wearing out of the machine is decreased.

A preferred embodiment of a machine adapted for executing the process according to the invention is shown in the accompanying drawings.

Fig. 1 shows a plan view of the machine.

Fig. 2 shows the position of a bunch in relation to a wrapper when the wrapping operation begins.

Fig. 3 shows in an enlarged scale a cross-section on the line A—B in Fig. 1.

Fig. 4 shows a plan view of a modification of a device according to the invention.

Fig. 5 shows a cross-section of the modification according to Fig. 4.

Beside the cigar machine proper a bunch producing device 1 is positioned. The cigar machine is provided with a buncher consisting of two rotatable drums 2 and 3 provided at their periphery with moulds 13 which latter have the same shape as the bunches. An arm 4 is secured to a rotatable shaft 5 journaled in the machine frame 12. A toothed segment 34 is keyed to the shaft 5 and meshes with another toothed segment 35 on a bell-crank lever 36 pivoted to a pin 37. The free end of the bell-crank lever has a roller 38 which runs in a curved groove 39 in a cam 40 which is keyed to a rotatable drive shaft 41, the latter being driven in any convenient manner from a drive source, thereby imparting reciprocating swinging movements to the arm 4.

Another vertical shaft 19 is also rotatably journaled in the frame 12 and carries an arm 9. A toothed segment 42 is keyed to the shaft 19 and meshes with another toothed segment 43 on a bell-crank lever 44 pivoted to a pin 45. The free end of the bell-crank lever has a roller 46 which runs in a curved groove 47 in a cam 48 which is keyed to the shaft 41 which thus imparts reciprocating swinging movements to the arm 9.

The arms 4 and 9 respectively are provided with retaining holders having pinchers 20 pivoted to plates 21 on the arms and forced together by springs 23. Each pincher 20 has an upper projecting lug 49. The pinchers of the arm 9 are provided each with a thin slot 22 permitting the engagement of a cutter blade 10 on the frame 12.

The machine is also provided with a device for cutting off the clippings from the wrapped cigar, said device comprising scissor-blades 7 and 8 arranged on the path of the swinging arm 9, and actuated in any well-known manner, for instance by means of a pin 50 engaging slots 51 in the blades 7 and 8 respectively. The blades are fulcrumed at 52 and a rod 53 carries the pin 50. Vertical reciprocating movements are imparted to the rod 53 in any manner well known in the art and therefore description thereof is not needed herein.

For cutting the wrapper a cutting device such as a die shell 29 is provided on the frame 12. A leaf carrier 30 is provided on a swinging arm 31 which is carried by a vertical shaft 32 which is also rotatably journaled in the frame 12 and carries a toothed segment 54 meshing with another toothed segment 55 on a double-armed lever 56 fulcrumed at 57 and having a roller 58 on its free end which engages a curved groove 59 in a cam 60 keyed to the shaft 41. Thereby reciprocating swinging movements are imparted to the arm 31 on the continuous rotary movement of the shaft 41. A cigar-wrapping device 6 is provided having a cluster developed and driven in any manner well known in the art and therefore needing no description herein. Finally a container 11 is provided in the frame for receiving from the holders cigars which have passed the cutting devices. Shoulders 61 are positioned above the drum 3, the wrapping mechanism 6 and the container 11 in such manner that they engage the lugs 21 of the pinchers 20 as the arms 4 and 9 respectively are swung into a position above the stations mentioned, whereby the pinchers are opened and closed respectively.

tively for delivering or gripping a bunch or cigar.

In operating the machine above described, a bunch 14 produced in the device 1 is inserted in a mould 13 in the drum 2 and transferred from said drum to the other drum 3 in known manner. Then the pinchers of the arm 4 fetch the bunch from the drum 3 and transfer it to the rolling device 6 where it is provided with a wrapper. As according to an embodiment of the invention a bunch adapted for two cigars, each end of which forms the tip of one cigar, is treated, the dimensions and the shape of the bunch producing device, the buncher and the rolling device are accommodated to the purpose.

Before the wrapping of the bunch a tobacco leaf is applied on the die-shell 29 where a wrapper, the shape and dimensions of which are accommodated to that of the bunch, is cut out and the wrapper is caught by the leaf carrier 30, both processes being carried out in well known manner. It is well known that in order to ensure proper wrapping, the wrapper must be flexible and moist. The wrapper is transferred from the die-shell to the rolling device 6 by swinging the shaft 32 with the arm 31. During this transferring movement the leaf carrier passes a paste-container 33, where as well the one end 18 of the wrapper 16 as the middle portion 17 of the same is provided with paste. The hatchet surfaces in Fig. 2 show how the paste is applied on the wrapper. Paste is applied on the middle portion of the wrapper so that at both sides of the cut after dividing the wrapped bunch, the wrapper is firmly fixed to the bunch during the cutting although the bunch has got out of shape.

After having been wrapped the cigar-body is immediately caught by the pinchers 20, whereafter the arm 9 swings in the direction of the arrow against the cutters 7 and 8, which cut off clippings at both ends of the cigar. On the continued swinging movement of the arm 9 in the direction of the arrow, the wrapped bunch is divided by the knife 10 at the space 22 between the pinchers 20. This cutting operation should be performed while the wrapper is still moist in order to avoid tearing of the wrapper. Two finished cigars are thus obtained.

The cigars cut off remain in the pinchers 20, after having passed the knife 10 until they reach the container 11 during the swinging movement of the arm 9 and are delivered into said container.

Since the slot 22 of the pinchers 20 is very small a sufficient support is obtained for the cigars during the dividing operation and the cut surfaces will be smooth and a scratching of the tobacco is avoided.

Instead of a fixed knife 10 as shown in Fig. 1 it is of course possible to use a rotatable blade.

Said knife 10 may of course be applied anywhere on the travelling path of the cigar-body 15 between the rolling device 6 and the container 11, e. g. at the scissor-blades 7, 8.

The cigar-body may also be at rest during the dividing operation.

A device adapted for executing the process last mentioned is shown in Figs. 4 and 5.

The holder consists of two elements 24, 25, provided with longitudinal grooves and separated from each other by a thin space 26. In front of said space a pair of scissors is arranged. The elements 24, 25 may be turned over round a spindle 28.

The cigar-body is conveyed by the arm 9 to the

holder 24, 25, where it is divided by the scissor blades 27. Thereafter the holder turns over and delivers the finished cigars into the container 11 or to a descending surface leading to said container.

The device may also be arranged in the way that the cigar-bodies roll down into the groove of the holder from the rolling device.

It is also possible to make a bunch corresponding to the total length of more than two cigars, 10 by rolling a single wrapper round this bunch and dividing the cigar-body thus obtained into more than two cigars.

The number of cutting means 10 for dividing the cigar-body as well as the number of parts, 15 separated by thin spaces, of which the holder of the cigar-body consists, then of course is accommodated to the purpose.

What I claim is:—

1. In a cigar machine in combination, a cigar 20 wrapping mechanism to receive a bunch having a length corresponding to the total length of a plurality of cigars and to provide said bunch with a single moist wrapper, a cutter, and means for immediately transferring the wrapped bunch 25 from said wrapping device to the cutter, said means coacting with said cutter to divide said wrapped bunch into a plurality of finished cigars while the wrapper is still moist.

2. In a cigar machine in combination, a cigar 30 wrapping mechanism to receive a bunch having a length corresponding to the total length of a plurality of cigars and to provide said bunch with a single moist wrapper, a cigar dividing cutter, a clipping cutter, means for immediately transferring the wrapped bunch from said wrapping device into cutting position relative to said clipping cutter, said transfer means coacting with said dividing cutter to divide said wrapped bunch into a plurality of finished cigars while the 40 wrapper is still moist.

3. In a cigar machine in combination, a cigar 45 wrapping mechanism to receive a bunch having a length corresponding to the total length of a plurality of cigars and to provide said bunch with a single moist wrapper, a delivery station for finished cigars, means for immediately transferring the wrapped bunch from said wrapping device to said station, and a cutter adjacent the path of said transferring means, said means coacting with said cutter to divide said wrapped bunch into a plurality of finished cigars while the 50 wrapper is still moist.

4. In a cigar machine in combination, a cigar 55 wrapping mechanism to receive a bunch having a length corresponding to the total length of a plurality of cigars and to provide said bunch with a single moist wrapper, a delivery station for finished cigars, means for immediately transferring the wrapped bunch from said wrapping 60 device to said station, and a cutter adjacent the path of said transferring means, said means coacting with said cutter to divide said wrapped bunch in transit into a plurality of finished cigars while the wrapper is still moist.

5. In a cigar machine in combination, a cigar 65 wrapping mechanism to receive a bunch having a length corresponding to the total length of a plurality of cigars and to provide said bunch with a single moist wrapper, a wrapper cutter, means 70 for transferring a wrapper from said wrapper cutter and deliver it to a bunch in said wrapping mechanism, a cigar dividing cutter, and means for transferring the wrapped bunch from said wrapping device to the cigar cutter and coacting 75

with said cigar cutter to divide said wrapper bunch into a plurality of finished cigars while the wrapper is still moist.

6. In a cigar machine in combination, a cigar wrapping mechanism to receive a bunch having a length corresponding to the total length of a plurality of cigars and to provide said bunch with a single moist wrapper, a wrapper cutter, means for transferring a wrapper from said wrapper cutter and deliver it to a bunch in said wrapping mechanism, a paste supplying device adjacent the path of said wrapper transferring means for coating with said means to supply an adhesive to said wrapper, a cigar dividing cutter, and means for immediately transferring the wrapped bunch from said wrapping device to the cigar cutter and coating with said cigar cutter to divide said wrapped bunch into a plurality of finished cigars while the wrapper is still moist.

7. In a cigar machine in combination, a cigar wrapping mechanism to receive a bunch having a length corresponding to the total length of a plurality of cigars and to provide said bunch with a single moist wrapper, a cutter, and means for immediately transferring the wrapped bunch from said wrapping device to the cutter, said means coating with said cutter to divide said wrapped bunch into a plurality of finished cigars while the wrapper is still moist, said transfer means having a thin slot therein for accommodating said cutter.

8. In a cigar machine in combination, a cigar wrapping mechanism to receive a bunch having a length corresponding to the total length of a plurality of cigars and to provide said bunch with a single moist wrapper, a cutter, a holder adjacent said cutter, and means for immediately

transferring the wrapped bunch from said wrapping device to a cutting position in said holder to divide said wrapped bunch into a plurality of finished cigars while the wrapper is still moist.

9. In a cigar machine in combination, a cigar wrapping mechanism to receive a bunch having a length corresponding to the total length of a plurality of cigars and to provide said bunch with a single moist wrapper, a cutter, a holder adjacent said cutter, and means for transferring the wrapped bunch from said wrapping device to a cutting position in said holder to divide said wrapped bunch into a plurality of finished cigars while the wrapper is still moist, said holder being adapted to be tilted.

10. In a cigar machine in combination, a cigar wrapping mechanism to receive a bunch having a length corresponding to the total length of a plurality of cigars and to provide said bunch with a single moist wrapper, a cutter, a holder adjacent said cutter, and means for immediately transferring the wrapped bunch from said wrapping device to a cutting position in said holder to divide said wrapped bunch into a plurality of finished cigars while the wrapper is still moist, said holder having a thin slot for accommodating said cutter.

11. In a cigar machine, a cigar wrapping mechanism to receive a bunch having a length corresponding to the total length of a plurality of cigars and to provide said bunch with a single moist wrapper, and means for immediately transferring the wrapped bunch from said wrapping mechanism and dividing it into a plurality of finished cigars while the wrapper is still moist.

ERNST RUBEN DAHLSTRÖM.
